UNITED STATES PATENT OFFICE

EDWARD RENICK, OF DAYTON, OHIO, ASSIGNOR TO THE STANLEY MANUFACTURING COMPANY, OF DAYTON, OHIO, A CORPORATION OF OHIO

APPARATUS AND METHOD OF MAKING COLORED LABELS

Application filed August 14, 1929. Serial No. 385,903.

My invention relates to apparatus and method of manufacturing labels.

It is an object of my invention to provide means and method of applying a decorative coating to metal labels.

It is a further object to provide means of printing and embossing a design and a wet color upon a continuous strip of metal, simultaneously cutting the design from the metal strip, but allowing it to remain with the metal strip and then applying a dry dust coating evenly over the metal labels thus formed, working this dust into the surface of the labels and removing the surplus dust as well as removing the labels from the metal strip.

Referring to the drawings:

Fig. 1 is a side elevation of the complete apparatus;

Fig. 2 is a top plan view thereof;

Fig. 3 is a section on the line 3—3 of Fig. 2, with one of the side walls removed from the machine;

Fig. 4 is a section on the line 4—4 of Fig. 2;

Fig. 5 is a diagrammatic plan view of the labels in the successive stages of coloring;

Fig. 6 is a section on the line 6—6 of Fig. 5.

Referring to the drawings in detail, 1 is an endless belt of flexible material and 2 is a

strip of metal from which labels are made. The belt 1 and the strip 2 pass over the guide roller 3 of the reciprocating press head 4. A stationary die head 5 is provided with an embossing and cutting surface 6, the indentations of which are filled with a predetermined color by the reciprocating rolls 7 which reciprocate over the surface 6 after having picked up the coloring from the distribution roll 8 that is fed from the reservoir 9 by distributing the rolls 10 with a smooth coating of coloring.

The result of moving upwardly of the head 4 after the color rolls 7 have imparted color to the embossing and cutting mechanism 6 is that a label 11 having embossed margin 12 with a color area 13 is produced. While this label is severed from the strip 2 yet it remains in position in the strip without being separated therefrom as it is carried along on the belt 1. In the process of

being thus carried along it receives a heavy coating of dust of some suitable color, such as 14. This dust is applied through a reciprocating sifting can 15 having sifting openings 16 and a filler opening 17. The can is mounted upon an axle 18 that is journaled in the side walls 19 or upon brackets of any suitable design. Connected to this axle 18 is a lever arm 20 to which in turn is pivoted the reciprocating pitman 21. This pitman is connected by the link 22 to an arm 23 on a motor driven shaft 24. The shaft is carried in suitable journaled brackets 25 by the bottom plate 26 which also supports the side walls 19. The shaft is driven by the gears 27 and 28. Gear 28 is mounted on the armature shaft 29 of the motor 30. A bevel gear 31 is also mounted on this shaft which engages with a second bevel gear 32 that drives a vertical shaft 33 and pulley 34. The pulley 34 drives the belt 35 and the pulley 36 mounted on the rotating brush shaft 37. This brush shaft is carried on a transverse plate 38 resting on the side walls 19. The shaft 37 also carries a rotating brush head 39 having a plurality of brushes 40 which serve during their rotation to work the dust 14 as at 41, thoroughly into the surface 13 on which is deposited the dust 14.

When this has been done the dusted labels are carried beneath a series of reciprocating brushes 42 which remove the surplus dust. Such reciprocating brushes are mounted in rocking cradles 43 in which they are located by set screw 44. These cradles are journaled at 45 in the side walls 19 and are connected by arms 46 and pins 47, which pins project through slots on the side walls 19 to the reciprocating pitman 21. It will be understood that this link mechanism may be located inside of the side walls 19 or outside, as desired.

After the brushes have taken off as much of the surplus dust as possible, as indicated at 48, the labels pass beneath the vacuum cleaner head 49 where they have the appearance of evenly arranged dust, as at 50. The labels are dropped into the hopper 51 while the metal strip 2 from which the labels have been punched passes downwardly into scrap. 10c

Suitably driven rollers 52 serve to actuate the conveyor belt 1. The details of driving this belt are not important. I have shown the inking mechanism for the die and punch mechanism diagrammatically as the details of its operation are not essential in this connection.

It will be understood that I desire to comprehend within my invention and within the scope of my claims such modifications as may be fairly comprehended within such claims and invention due to necessary modifications to adapt my invention to varying conditions of use and to varying purposes.

Having thus fully described my invention, what I claim as new and desire to secure by Letters Patent, is:

1. In a method of producing labels, forming blanks from a strip of material embossing, dusting the blanks with color, working the color onto the surface of the blanks to form labels and removing the surplus dust and removing the finished labels from the strip.

2. In a method of producing labels, forming label blanks from a strip of material applying to the blanks a predetermined form of wet color, dusting with dry color, working the dry dust into the first-mentioned colored surface evenly throughout and removing the surplus dust and removing the finished labels from the strip.

3. In a method of making labels, simultaneously cutting designs from a metal strip embossing them and applying wet color to the unembossed portions, dusting with dry dust the depressed colored areas while the designs are being moved by the movement of the strip, working the dry dust evenly over the depressed areas into the wet color and removing the surplus dust from the depressed areas.

4. In a method of making labels, simultaneously cutting designs from a metal strip embossing them and applying wet color to the unembossed portions, dusting with dry dust the depressed colored areas while the designs are being moved by the movement of the strip, working the dry dust evenly over the depressed areas into the wet color and sucking the surplus dust from the depressed areas.

5. In an apparatus for producing colored labels, means to color the labels, means to dust colored dust thereon, rotating brush means for brushing the dust therein evenly and reciprocating brush means for removing the surplus dust.

6. In an apparatus for producing colored labels, means to color the labels, means to dust colored dust thereon, rotating brush means for brushing dust therein evenly, reciprocating brush means for removing the surplus dust and suction means for removing the remaining free dust.

7. In combination, an endless conveyor adapted to convey a strip of metal, means for severing embossing and coloring a certain area on said strip while carried by the conveyor, means for dusting dry color on such area, means for working in such dry dust in the area and means for removing said surplus dust.

8. In an apparatus for manufacturing colored labels, an endless conveyor strip adapted to convey a metal strip, means for simultaneously embossing, color coating and severing labels from the metal strip while on the conveyor strip, means for dusting the labels while still on the strip from which they have been severed, means for working the dry dust so dusted into said coating, means for brushing the surplus dust therefrom and means for removing the labels from the metal strip and the conveyor.

9. In an apparatus for manufacturing colored labels, an endless conveyor strip adapted to convey a metal strip, means for simultaneously embossing, color coating and severing the labels from the metal strip while on the conveyor strip, means for dusting the labels while still on the strip from which they have been severed, means for working the dry dust so dusted into said coating, means for brushing the surplus dust therefrom, means for removing the labels from the metal strip and the conveyor and vacuum means for sucking said surplus dust from the labels prior to removal from the strip.

10. In combination, an endless conveyor strip adapted to convey a metal strip thereon means to sever labels from the strip, means by which the labels are embossed and color coated, a reciprocating dust container, a rotating brush, reciprocating brushing means and a common power means for operating the dusting, the rotating brush and the reciprocating brushing means, said labels being moved by the strip while being dusted and brushed.

11. In combination, an endless conveyor strip adapted to convey a metal strip thereon from which the labels have been severed, embossed and color coated, a reciprocating dust container, a rotating brush, reciprocating brushing means, a common power means for operating the dusting, rotating, brushing and reciprocating brushing means, said common means comprising a pitman connected to the dusting and reciprocating brushing means, a motor for reciprocating said pitman, means for pivotally supporting said dusting means and reciprocating brush means, and means operated by said motor for operating said rotary brushing means.

12. In combination, a stationary table, a moving conveyor strip moving thereover adapted to convey a metal strip carried thereby having labels contained thereon, em-

bossed, color coated and severed from but carried by the strip, means for dusting said labels, rotary means for working the dust therein, reciprocating brush means for removing said surplus dust and a common operating means for the dusting, rotary and reciprocating means.

13. In combination, a stationary table, a moving conveyor strip moving thereover adapted to convey a metal strip carried thereby having labels contained thereon, embossed, color coated and severed from but carried as part of the strip, means for dusting said labels, rotary means for working the dust therein, reciprocating brush means for removing said surplus dust, a common operating means for the dusting, rotary and reciprocating means, and vacuum means for removing the surplus dust.

14. In combination, a stationary table, a moving conveyor strip moving thereover, adapted to convey a metal strip carried thereby having labels contained thereon, embossed, color coated and severed therefrom but carried as part of the strip, means for dusting said labels, rotary means for working the dust therein, reciprocating brushing means for removing said surplus dust, a common operating means for the dusting, rotary and reciprocating means, vacuum means for removing the surplus dust and means for removing the labels from the metal strip.

15. In combination, a stationary table, a moving conveyor belt thereover adapted to convey a metallic strip containing labels severed therefrom but not removed therefrom, side walls for said table, a reciprocating sifter can closely adjacent the said metal strip, a rotating brush head for working the dust sifted from the can onto the labels on the strip, rocking frames connected to the sifter can journaled in the side walls of the table, brushes carried by said rocking frames detachably mounted therein for reciprocatory movement over the dusted labels, means for imparting reciprocatory movement to said can and brushes comprising a pitman and motor-driven means for actuating said pitman and pulley, and a belt system driven by said motor for actuating said rotary brush means.

16. In combination, a stationary table, a moving conveyor belt thereover adapted to convey a metallic strip containing labels severed therefrom but not removed therefrom, side walls for said table, a reciprocating sifter can closely adjacent the said metal strip, a rotating brush head for working the dust sifted from the can onto the labels on the strip, rocking frames connected to the sifter can journaled in the side walls of the table, brushes carried by said rocking frames detachably mounted therein for reciprocatory movement over the dust labels, means for imparting reciprocatory movement to

said can and brushes comprising a pitman and motor-driven means for actuating said pitman and pulley, a belt system driven by said motor for actuating said rotary brush means and means for moving said belt and metallic strip with the labels beneath said sifter and brushes.

In testimony whereof, I affix my signature.
EDWARD RENICK.
